UNITED STATES PATENT OFFICE.

WILLIAM C. BAKER, OF NEW YORK, N. Y., ASSIGNOR TO THE BAKER
HEATER COMPANY, OF SAME PLACE.

SAFETY-VENT FOR STEAM-BOILERS.

SPECIFICATION forming part of Letters Patent No. 372,289, dated November 1, 1887.

Application filed February 12, 1886. Serial No. 101,714. (No model.)

To all whom it may concern:

Be it known that I, WILLIAM C. BAKER, of the city and State of New York, have invented an Improvement in Safety-Vents for Steam-Boilers, &c., of which the following is a specification.

In the use of safety-valves there is danger in consequence of the uncertainty of the action. The valve is liable to adhere to the seat in consequence of oxidation and the presence of foreign matter, or otherwise. Besides this, the valve may be fastened down or over-weighted. Plates of metal have been secured by rings to cases in which the steam is allowed to act; but the pressure required for opening the vent will often depend upon the force with which the metal plate is bolted and held by the clamping-rings. Where fusible alloy is employed, the same may be exposed to the action of currents of air or other chilling influence that keep the metal at a less temperature than the steam, and the fusing-point is sometimes changed during the lapse of time.

My present invention is especially adapted to the heating apparatus made use of in railway-cars, where danger arises from carelessness on the part of the porter or other attendant. In the heating apparatus of railway-cars it has been usual to place an expansion-vessel above the roof of the car and to connect the safety-valve with the same. In this position the safety-valve is not easily accessible, and it is liable to become obstructed, and it is seldom examined to ascertain whether it is in proper condition.

My improvement relates to a safety-vent made of a metallic case, preferably of cast-iron, connected by a tube to the boiler, heating apparatus, or other generator that is to be protected from explosion; and this safety-vent is in the form of a hollow bulb, the lower portion of which is sufficiently heavy and strong to be firmly attached to the vent-pipe, and the upper part is reduced in thickness, so as to be considerably weaker than any other portion of the apparatus with which it is connected, thereby allowing for the upper portion of the vent-bulb being broken away and blown off by an excess of pressure, so that the steam or other fluid is allowed to issue freely through

the vent-pipe and reduce the pressure in the generator. The exterior of this safety-vent, being smooth, can be plated, coated, or painted, so as to protect it from atmospheric influences, and it is of very trifling expense to manufacture; and in case of over-pressure the breaking and the immediate reduction of the pressure is absolutely certain, and the removal of the broken safety-vent and the substitution of a new one occupies but a few moments, and can be done either by hand or by a wrench.

In the drawings, Figure 1 is a vertical section of the safety-vent and a portion of the tube leading to the boiler or other generator, and Fig. 2 is an inverted plan of the same.

The safety-vent is preferably a hollow flattened spheroid, and the lower side, A, of the same and the circular sides B are of sufficiently thick material to correspond in strength with the pipes and other parts made use of in the heating or other apparatus; but the top C of the safety-vent is considerably reduced in thickness, so that its strength is diminished to any desired extent. I prefer to mount this bulb in a lathe and turn off the interior surface of the top or diaphragm C with a suitable tool, and then to true off the exterior surface of the disk or top and reduce the thickness to whatever extent is necessary, so that the breaking-point of the disk portion of the safety-vent may correspond with the desired maximum pressure. This is readily determined by measuring the thickness of the disk portion and subjecting the vent-bulb to the action of hydraulic or other pressure until the disk is torn open or blown off. Safety-vents having a corresponding thickness will always be sufficiently reliable for use with the given pressure to which they are adapted, because, in case of imperfection in the metal, the worst result that can happen will be the breaking of the safety-vent at a less pressure than that intended.

In order to give access for turning off the inner surface of the disk portion, it is preferable to make use of a large opening in the base or bottom of the safety-vent and to screw-thread the metal and introduce a reducing-nut, E, between the bottom portion, A, of the safety-vent and the tube F, leading to the boiler or other apparatus.

Usually it is preferable to make use of a safety-vent the exterior surface of which is plain or smooth, so that the bulb can be grasped and unscrewed or replaced by hand without the use of a wrench; but the reducing-nut E should have a square surface, upon which a wrench can be applied for screwing the same upon a pipe or unscrewing it, when necessary.

The shape of this safety-vent may vary and may be either circular or polygonal, and it may be made in the form of a ring, with the edges sufficiently thick to allow for attachment to the place where the steam, compressed air, or other fluid will act upon one side. The size and thickness of this safety-vent may be varied according to the capacity of the boiler or other generator and the pressure that it is exposed to.

I claim as my invention—

1. A hollow safety-bulb formed of one piece of metal, with a thick strong portion to which the pipe leading to the generator or source of pressure is connected and a thinner portion the outer and inner surfaces of which are turned off or trued to render the metal of uniform thickness where the rupture is to take place under excessive pressure, substantially as set forth.

2. A hollow safety-bulb formed of one piece of metal, with a thick strong portion to which the pipe leading to the source of pressure is connected and a thinner portion, to break away by excessive pressure, both surfaces of which thinner portion are turned off or trued to render the metal of uniform thickness where the rupture is to take place, the thickened portion having a screw-thread for the pipe-connection and a large opening to give access for turning off the inner surface, substantially as set forth.

3. The combination, with the pipe connecting to the source of pressure and the nut E thereon, of the hollow safety-bulb screwed upon the nut and having a thick strong edge and a thinner portion the outer and inner surfaces of which are turned off or trued to render the metal of uniform thickness where the rupture from excessive pressure is to take place, substantially as set forth.

Signed by me this 9th day of February, 50
A. D. 1886.

W. C. BAKER.
